UNITED STATES PATENT OFFICE

MARTIN L. HARGER, OF NEWELL, PENNSYLVANIA, ASSIGNOR OF ONE-THIRD TO CHARLES O. DOWNER, OF NEWELL, PENNSYLVANIA, AND ONE-THIRD TO KERFOOT W. DALY, OF CHARLEROI, PENNSYLVANIA

JOURNAL BOX

Application filed October 31, 1927. Serial No. 229,844.

This invention relates to journal boxes for vehicles and has been particularly developed in its application to journal boxes for railway cars for transporting ore and other commodities in bulk, and which at the place of delivery are not uncommonly emptied by raising the cars bodily and overturning them. Suitable apparatus is in such case provided for engaging the entire car and 10 raising and inverting it. The invention resides primarily in the form given the journal box. Secondarily, it includes lubricating apparatus, capable of conjoint use with the box form in which the invention primarily is found. The lubricating apparatus, so conjointly useful, is capable also of independent use.

In the accompanying drawings Fig. I is a view in vertical section and on the axial line 20 of the car axle, through a journal box embodying my invention. Fig. II is a horizontal section in the plane indicated at II-II, Fig. I. Fig. III is a view in transverse section, on the plane indicated at III-III, 25 Fig. I.

Referring to Fig. I, the journal box as a whole is indicated by the numeral 1, in assembled position with the axle of a car, which axle is indicated by the numeral 2. 30 From the showing of Figs. I and III, the bearing block has, for purposes of illustration, been omitted. It will be understood that the block is in the complete assembly interposed between the surface of the axle and 35 the upper wall of the journal box. In Fig. I the box is shown to be open at 16. A proper closure for this opening will of course be provided.

The journal box, as will be seen, is of the 40 general shape now familiar, for it is desirable that it conform to the standard of the American Railway Association, and it contains the following particular provisions. It includes, within, a false bottom 3 which 45 slopes from the inner and outer walls of the box downwardly toward the center, where there is an opening. Between this false bottom 3 and the true bottom 4 of the box a well is formed. At the outer end of the box a 50 pocket 5 constitutes an enlargement of the

well space, and so, similarly, at the inner end, the well is made continuous with pockets 6 which extend on either side of the axle. The car ordinarily is overturned laterally; and it will be understood that, given the 55 structure described, provided with a quantity of oil less than sufficient to submerge the false bottom 3, substantially all of the oil will, upon the overturning of the car, flow into one or more of the pockets 5 and 6, 60 and be retained there. On restoration of the car to normal position the oil will return to the bottom of the well.

Supplementing the effect of the sloping false bottom 3 in carrying the oil when the 65 car is inverted, into the pockets 5 and 6, 6, small downwardly inclined lips 11 and 12 are provided within the journal box and at the inner and outer ends of the box and above the false bottom 3. These lips will 70 serve, when the car is inverted, to retain what small quantities of oil may be found above the false bottom, and prevent any appreciable spilling of it. The lip 12 is prolonged semi-circularly, as will be seen on comparing the drawings one with another, to the 75 end that when the car is inverted, surplus oil may not dribble over the axle and be wasted, but may be carried to and retained in the upper part of the box.

For the purpose of carrying the oil to and distributing it upon the bearing surface of the axle 2, when the car is in normal position and running, a distributing disk 7 is provided. This distributing disk 7 is rotatable in bearing blocks 8, which are mounted in guides 9, and backed by springs 10. The disk 7 is mounted beneath the axle with its own axis in parallelism with that of axle 2. It depends at its lower periphery into the 90 body of oil maintained in the journal box beneath the false bottom 3, and it bears under spring tension tangentially upon the axle. As the car travels and as the axle 2 rotates, the disk 7 by its tangency upon the axle is 95 caused to rotate on its own axis, and as it rotates it carries oil from the well into which it depends, to, and distributes it upon, the bearing surface of the axle 2.

The particular shape of the disk 7 is such 100

as to transfer from the well relatively large quantities of oil to the bearing surface of the car axle. To this end the disk has a relatively broad face, and its face is grooved into shallow, rounded undulations, and the disk is 5 thickest at its rim.

More particularly, the face of the disk is provided with a medial crest 13 of maximum diameter, and upon this medial crest 13 the 10 disk makes tangency upon the axle 2. From crest 13 the face of the disk recedes on gentle curves, and rises again to two marginal crests 14 of somewhat less, though not greatly less, diameter. In consequence of these details of 15 shape, when the car is moving at relatively slow speed, the oil (which will be of relatively heavy and viscous nature) will tend to flow over the face of the disk and pass to the axle in two streams, on either side of crest 20 13. And when speed increases, the augmented flow of oil will be chiefly centrifugal, from the two minor crests 14 directly to the axle.

The box is preferably provided with a bottom opening, normally closed by a removable 25 plate 15. Upon this plate 15 the guides 9 rest, and the bottom opening is of sufficient size that the lubricating apparatus may be withdrawn through it. This bottom opening affords access to the interior of the box, for 30 all purposes, including that of the insertion and removal of the lubricating apparatus.

The journal box of this invention is intended to be used without the usual packing of waste, and is intended to avoid and prevent 35 the great losses with which railways now have to deal, consequent upon hot boxes.

In operation, the well in the bottom of the box is filled with lubricating oil (which, as has been said, is relatively heavy and viscous 40 in nature) preferably to a level near though somewhat below the level of the opening through the false bottom 3. As the car travels, the disk 7, which conveniently is journaled substantially in the opening in the false bottom, bearing at its periphery yieldingly 45 upon the axle 2, is rotated by the turning axle. Since it dips into the body of oil beneath, it carries the oil as it rotates, and feeds it to the axle. As speed increases, the increased 50 volume of oil fed is more widely spread upon the axle. The oil which drips from the axle drains back, by virtue of the sloping false bottom 3, into the well beneath. When the car is overturned laterally substantially 55 all the oil within the well is displaced and stored in the pockets 5 or 6, 6, whence it returns when the car is righted again. Such small quantities of oil as on the overturning escape through the opening in 60 the false bottom, flow to right or left, as the case may be, and are caught by the wings 11 and 12, and returned, when the car is righted again, to the well.

I claim as my invention:

65 1. A journal box for a car axle containing

within its walls a false bottom which extends in the direction of the length of the axle to which the box when in service is applied, from the opposite inner and outer journal-box walls to an intermediate opening, and oil-retaining pockets formed with the journal-box walls and at the inner and outer ends of the journal box, with which pockets the space beneath the false bottom is at the inner and outer ends thereof in communication. 70

2. A journal box for a car axle including a false bottom which slopes downwardly from the parted wall of the journal box to an opening, and a downwardly sloping lip extending at greater height from the box wall and in its extent conforming to the shape of the wall port. 75

In testimony whereof I have hereunto set my hand.
